(57) **CLAIM**

The ornamental design for a combined transmitter and receiver for locating pet, as shown and described.

DESCRIPTION

FIG. 1 is a top, front, right perspective view of a combined transmitter and receiver for locating pet, showing my design.

FIG. 2 is a bottom, rear, left perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a perspective view thereof, shown in an unfolded state of the transmitter's antenna of the combined transmitter and receiver for locating pet.

The details shown in broken lines form no part of the claimed design.
